UNITED STATES PATENT OFFICE

2,637,888

APPARATUS FOR PRODUCING CONCRETE
ROOF TILESAlbert Louis Bushore, Riverside, Calif., assignor
to Frank J. Hart, San Bernardino, Calif.

Application May 4, 1950, Serial No. 160,056

3 Claims. (Cl. 25—43)

1

The invention consists in a new and useful improvement in apparatus for producing concrete roof tiles. The improved apparatus is so designed that a dense, compact, waterproof tile can be made without hand tamping or hand troweling. A novel form of hopper feeds a wet mix of concrete to a pallet and a blade cuts the concrete, leaving the proper thickness on the pallet, and as the pallet is withdrawn from under the hopper trowels which are mounted adjacent the blade trowel the concrete, producing a waterproof bright finish on the tile. The particularly novel and useful features of the improved apparatus are the peculiar form of the hopper whereby the pallet is properly charged with the material for producing the tiles, the pallet carriage for moving the pallet into and out of charging position relative to the hopper, the blade and trowel carriage co-acting with the pallet carriage whereby the blade moved by its carriage cuts the concrete to the determined thickness for the tiles, and the trowels held by their carriage trowel the material on the pallet moved by its carriage, and the novel combination of said elements in a single, simple, sturdy structure.

While one specific embodiment of the invention is illustrated in the drawings and herein-after fully described, it is to be distinctly understood that the scope of said invention is not limited to said embodiment but is defined by the claims appended hereto.

In the drawings:

Fig. 1 is a perspective of the improved apparatus showing a completed tile ready to be removed from the apparatus.

Fig. 2 is a fragmentary side elevation of the base of the apparatus, its casing being removed.

Fig. 3 is a horizontal section on the line 3—3 of Fig. 2, in the direction of the arrows, some of the operating elements which are shown in Fig. 2 being removed.

Fig. 4 is a fragmentary side elevation of the upper portion of the base and the feed hopper.

Fig. 5 is a front elevation of the structure shown in Fig. 4.

Fig. 6 is a vertical section on the line 6—6 of Fig. 5, in the direction of the arrows, the two carriages being shown below the hopper.

Fig. 7 is an enlarged top plan of the blade and trowel carriage, and the blade and trowels.

Fig. 8 is an enlarged top plan of the pallet carriage.

Fig. 9 is a greatly enlarged vertical section on the line 9—9 of Fig. 8, in the direction of the arrows.

2

As illustrated in the drawings, the apparatus has a base B (Figs. 2 and 3) comprising four upright posts 1 on which is mounted a rectangular frame F having side rails 2 and 3 and rear and front rails 4 and 5. The upper portion of the base B (Figs. 4 and 5) comprises a rectangular frame F-1 formed by upright corner angle-irons 6 on the rails 2 and 3 and transverse angle-irons 7 bolted to the angle-irons 6. Angle-irons 8, normal to and bolted on the angle-irons 7, complete the frame F-1 forming the upper portion of the base B. Suitably mounted on the frame F-1, there is a feed hopper 9 of novel form. The hopper 9 (Figs. 1, 4 and 5) has downwardly diverging walls 9-a which are fixed at their lower edges to the angle-irons 7 by any suitable means, as by welding, and downwardly diverging walls 9-b similarly fixed to the angle-irons 8. Each wall 9-b has a vertically disposed strengthening rib 9-c. The hopper 9 has a flaring intake 9-d projecting upwardly from the walls 9-a and 9-b. The portion of the hopper 9 below the angle-irons 7 and 8 and within the frame F-1 has vertical walls 9-e projecting downwardly from the lower edges of the walls 9-a and 9-b, and its lower discharge end 10 is disposed centrally of the frame F-1.

The base B has mounted therein a platform 11 on which is hingedly mounted a swingable platform 12 oscillatable by a head 13 on a lever 14 pivoted in the base B. Suitably journaled on the platform 12 there is a shaft 15 having a pulley 16 driven by a belt 17 on a motor M mounted on the platform 11. A suitable fly-wheel 18 is provided on the shaft 15. An eccentric 19 on the shaft 15 co-acts with a roller 20 (Fig. 5) suitably journaled in a suitable support 21 depending from the frame F-1, to vibrate frame F-1 and the hopper 9 when lever 14 is rocked to cause head 13 to raise platform 12 to move eccentric 19 to engage roller 20.

The base B has a suitable casing C (Fig. 1) enclosing the base B up to the upper edge of the frame F. A casing C-1 extends forwardly of the base B and has side walls 22 and a front wall 23. The forward end of the lever 14 projects through a slot 23' in the wall 23 and has a suitable pedal 14' on its outwardly projected end.

Suitably mounted on the angle-irons 6 at the lower end of the frame F-1, there is a pair of angle-irons 24 (Figs. 1, 4 and 5) provided with tracks 25, respectively. The forward ends of the angle-irons 24 are supported on a bracket 26 on the upper edge of the front wall 23 of the casing C-1. Suitably mounted on the angle-irons

6 at the upper end of the frame F-1, there is a pair of angle-irons 27 (Figs. 1, 4 and 5) provided with tracks 28, respectively. Tracks 25 extend outwardly from tracks 28 to dispose carriage 29 for removal of the pallet.

A pallet carriage 29 (Figs. 1 and 8) is slidably mounted on the tracks 25 by means of rollers 30 and has a suitable frame 31 with adjustable screws 31-a to serve as a holder for the pallet 32 (Fig. 1), and a transverse handle bar 33 at its front end. A spring-pressed latch 34 (Figs. 8 and 9) is provided at the left end of the bar 33 to co-act with a latch socket 35 on the left-hand front angle-iron 6 (Fig. 1) for locking the carriage 29 in its rear position to dispose the pallet 32 under the feed hopper 9.

A blade and trowel carriage 36 is slidably mounted on the tracks 28 by means of rollers 37. (Figs. 1 and 7.) Guard rails 38 (Fig. 1) having inverted U-shaped cross-sections are mounted on the angle-irons 6 and rollers 39 (Fig. 7) on the carriage 36 co-act with the rails 38 to retain the carriage 36 on the rails 28. Rollers 40 (Fig. 8) on the carriage 29 co-act with the lower faces 41 of the angle-irons 27 to retain the carriage 29 on the rails 25.

The carriage 36 (Fig. 7) has mounted therein by means of bolts 42 a blade 43 and also adjustably mounted therein a pair of trowels 44. Each trowel 44 has a body comprising a plate 44-a and end flanges 44-b, and a blade 44-c of suitable form mounted on the body 44-a. A rod 45 mounted in the sides 36-a of the carriage 36 passes through registering circular openings in the flanges 44-b of the trowel 44 to support the trowel in the carriage. Bolts 46 tapped into the sides 36-a pass through slots in the flanges 44-b of the trowel 44 and nuts 47 on the bolts 46 fix the trowel 44 in adjusted relation to the carriage 36.

The carriage 36 has a latch 48 (Figs. 1 and 7) pivoted in a bracket 49 on a cross-piece 36-b of the carriage 36 intermediate the blade 43 and the trowels 44. A spring 50 mounted on the cross-piece 36-b biases the latch 48 to co-act with a latch socket 51 on the frame F-1 (Fig. 5) to lock the carriage 36 in its rear position to dispose the blade 43 under the feed hopper 9. A rod 52 connects the latch 48 with a handle 53 pivoted on the front cross-piece 36-c of the carriage 36. A spring 54 is interposed between the cross-piece 36-c and the handle 53 to bias the handle 53 to hold the latch 48 in operative position.

A spray-head 55 (Figs. 1 and 2) is suitably mounted in the casing C-1 and so disposed as to spray water under pressure against the blades 44-c of the trowels 44 when the carriages 29 and 36 are in their rear positions. Water is supplied to the head 55 by a suitable conduit 56 in which there is a suitable control valve 57 operated by a rod 58 which projects through the front wall 23 of the casing C-1 and has on its projected end a presser plate 59. A coil spring 60 on the rod 58 is interposed between the wall 23 and the plate 59 to bias the rod 58 to normally close the valve 57.

A pair of brackets 61 (Figs. 2 and 3) mounted on the posts 1 of the base B extend into the casing C-1 to support a sleeve 62 which is braced by a pair of struts 63 also mounted on the posts 1. Slidably received in the sleeve 62 is a rod 64 on the top of which is mounted a suitable plate 65. The plate 65 is raised from its normal position resting on the upper end of the sleeve 62 by a lever 66 pivoted on the base B and connected to

the rod 64 by a suitable linkage 67. The lever 66 extends through an opening 23' in the front wall 23 of the casing C-1 and has on its outer end a pedal 68'.

5 A lug 68 (Figs. 5 and 6) is mounted in the rear part of the frame F-1 and so disposed as to support the rear end of the blade 43, so that the blade 43 is in close juxtaposition with the open end 10 of the hopper 9 when the carriage 36 is 10 in its rear position. A suitable discharge lip 69 (Fig. 1) is mounted on the lower edge of the frame F-1 below the tracks 25 to guide any drippings of surplus cement from the frame F-1 into a sump (not shown) in the casing C-1. A discharge port 70 is provided in the wall 22 of the casing C-1 for draining from the sump the cement and the wash water from head 55 into any suitable portable receptacle 71.

Having described the structural details of the 20 apparatus, its use and operation will now be described. The carriage 36 having been moved to its rear position, the blade 43 closes the discharge end 10 of the hopper 9. The hopper 9 is then charged with a suitable quantity of material suitable for producing the tiles. Experience in the 25 actual operation of the improved apparatus has demonstrated that the desirable material consists of a mixture of cement and sand with sufficient water to produce a wet mix which has a 30 tendency to pack without flowing. The pallet 32 having been disposed in the carriage 29, the carriage 29 is moved into frame F-1, to its rear position, and fixed in such position by the latch 34 in the socket 35. The carriage 36 is then 35 moved forwardly to remove the blade 43 from under the end 10 of the hopper 9. The lever 14 is rocked by depressing the pedal 68' and the motor M, being energized, rotates the shaft 15 causing the eccentric 13 to vibrate the frame F-1 40 and the hopper 9. This vibration causes the material in the hopper 9 to feed downwardly onto the pallet 32.

It is to be noted that the hopper 9, as above 45 described, is so designed that its cross-section increases downwardly, which allows the material to move downwardly without packing in the hopper 9. When this form of hopper is vibrated, the wet mix moves downwardly quickly and completely fills all of the depressions in the pallet 50 so that it then packs together filling all voids and permitting no air pockets, and consequently producing a tile so dense that it is waterproof.

The carriage 36 is then moved rearwardly, 55 causing the blade 43 to move between the material in the pallet 32 and the lower end 10 of the hopper 9. It is obvious that the adjustment of the pallet 32 by screws 31-a in the carriage 29 determines the desired thickness of the material on the pallet 32, thereby precisely measuring the 60 quantity of the material desired to form the tile. When the carriage 36 is in its rear position, the rear edge of the blade 43 being supported by the lug 68, it is locked in such position by the latch 48 in the socket 51. The valve 57 is then opened 65 by pressure applied to the plate 59 and water from the head 55 sprays the blades 44-c of the trowels 44 thoroughly wetting them. The latch 34 of the carriage 29 is then released and the carriage 29 is drawn forwardly, moving the mold 32 from under the blade 43 and passing it under the trowels 44. It is obvious that the adjusted 70 positions of the trowels 44 in the carriage 36 are such that the blades 44-c of the trowels 44 trowel the upper surface of the material on the pallet

32, producing a waterproof bright finish, thereby completing the production of the tile.

When the carriage 29 carrying the completed tile has reached its forward position (Fig. 1), the pallet 32 with the tile therein is disposed above the plate 65. The lever 66 is then rocked by depressing the pedal 66' thereby elevating the plate 65 which ejects the pallet 32 from the carriage 29, and the pallet 32 with the tile can be removed from the apparatus.

Having described my invention, what I claim is:

1. In an apparatus for producing tiles, the combination of a frame; a hopper mounted on said frame, and having a bottom discharge port; a track mounted on said frame and having a portion under said hopper and a second portion extending outwardly from said hopper; a second track mounted in said frame and having a portion under the first-mentioned portion of said first track, a second portion under the second-mentioned portion of said first track, and a third portion extending outwardly from said second-mentioned portion of said first track; a carriage mounted on said first track; a gate for opening and closing said discharge port, mounted on said carriage; a plurality of trowels mounted on said carriage; a second carriage mounted on said second track; a pallet removably mounted in said second carriage; and means for removing said pallet from said second carriage, the parts being so related that travel of the first carriage causes said gate to open and close said port, and travel of said second carriage disposes said pallet in charging position relative said hopper, automatically trowels the charge on said pallet, and disposes said pallet for functioning of said removing means.

2. In an apparatus for producing tiles, the combination of a frame; a hopper in said frame for material for producing tiles and having a bottom discharge port; means, slidable in said frame below said hopper for opening and clos-

ing said port and for troweling the tiles; a pallet slidable in said frame below said means; and means below said pallet for ejecting said pallet from said frame, the charging of material on the pallet, the troweling of the tiles and the positioning of the pallet for ejection being effected by sliding said opening and closing and troweling means, and by the sliding of said pallet.

- 10 3. In an apparatus for producing tiles, the combination of a frame; a hopper mounted on said frame, and having a bottom discharge port; a carriage below said hopper and slidable in said frame into and out of two positions of adjustment; a closure for said port carried by said carriage; troweling means carried by said carriage; a second carriage slidable in said frame below said first carriage into and out of three positions of adjustment; a pallet removably mounted in said second carriage; and means for removing said pallet from said second carriage, the parts being so related that the port is closed and opened when said first carriage is in its two positions of adjustment, respectively, the pallet is charged when the port is open and said second carriage in one of its positions, the charge on the pallet is troweled when said second carriage is moved into a second position, and said pallet is disposed for functioning of said removing means when said second carriage is in its third position.

ALBERT LOUIS BUSHORE.
